George H. Potter

Letter Patent Dated March 23, 1833.

The Scheme referred to in the Letter Patent, and making part of the same, containing a more exact description in the words of the said George H. Potter himself of his improvement in the mode of manufacturing Lead Pipes.

To all to whom these presents shall come:

Be it known that I George H. Potter of the Town of Olcott in the County of Steuben State of New York, have invented a new & useful improvement in the art of manufacturing Lead pipes, for the purpose of conveying fluids & gases & that the following is a full & exact description of the construction & operation of the machine as invented by me.

1st an apron of sheet iron six by 12, inches in an inclined situation to melt the lead upon. 2nd a square box b. of cast iron to which the apron a. is attached to receive the fusion, with two holes near the bottom on the side opposite the apron one half inch in diameter at c. c. each communicating with a separate pump t. D. which stand perpendicularly $\frac{1}{2}$ so constructed that they press alternately, the bore of each pump being three fourths of an inch in diameter.

At the bottom of the bore four inches below the communication with the box b. at c. c. is a hole in each pump c. t. communicating with a tight vessel in the form of a cylinder or square box of cast iron secured at each end by cast iron heads made fast by wrought ^{iron} bolts. In the inside of the cylinder at the mouths of the holes communicating with the pumps, are valves that play on a single point, so that the pressure of the piston in the pump, operating on the lead, drives the one part closes the other at the same

time, and thus alternately.

On the opposite side of the cylinder, at the bottom of the cylinder also, is a tube of cast iron attached to the base of cylinder by base the diameter of the base of cylinder is equal to the diameter of the pipe required. In the inside of the cylinder there are stands that support an iron rod, that passes thro' the center of the base of the tube & of a size equal to the bore required in the lead pipe or a screw on the end of the rod with a small well answer instead of the stands to support the rod in the center of the pipe.

The tube passes thro' a reservoir of water &c, sufficient to cool the pipe, as fast as it is pressed into the tube & is formed, from whence it is reeled or wound onto a reel or cylinder as fast as it is pressed out from the tube &c.

The piston of each pump is of cast iron and raises five inches from the bottom of the bore &c, & consequently one inch above the hole at C.C. and thus the bore of the pump between C.L. & C.C. has time to fill with the fusion of lead from the box B, & the gearing is so constructed that the piston 2, will pass below the hole C before its operation of pressing as soon as the piston 1, shall have ceased its pressure, so that a continued & steady pressure is maintained by means of wheels, part blank & part with teeth, that mesh into & interlock into a double rack attached to each piston, the wheel bringing up the rack, is larger than the other, but with the same number of teeth 3/4 of the same mesh & revolves in the same time & brings up the piston 2, in time, to have it carried down below the hole C, in the same time, that the piston 1 is passing from C to C, & thus alternately. The lead is kept from cooling by rods being placed around the apparatus necessary to be kept hot in an iron box, fitted to the apparatus, & as other models for working the apparatus may be applied with equal success your petition.

472

Claims most particularly the mode of pressing or receiving the fused lead into a tube around a rod, & cooling it in the passage thro' the tube in the manner before described, & thus forming the pipe. Dated at Chicago 26 July 1853.
